Primary Examiner — Selina Sikder(74) *Attorney, Agent, or Firm* — Omni Legal Group;
Omid E. Khalifeh; Ariana Sonloro(57) **CLAIM**

The ornamental design for a smart dimmer switch, as shown and described.

DESCRIPTION

FIG. 1 is a perspective view of a smart dimmer switch according to the present invention;

FIG. 2 is a front view of a smart dimmer switch according to the present invention;

FIG. 3 is a back view of a smart dimmer switch according to the present invention;

FIG. 4 is a first side view of a smart dimmer switch according to the present invention;

FIG. 5 is a second side view of a smart dimmer switch according to the present invention;

FIG. 6 is a third side view of a smart dimmer switch according to the present invention; and,

FIG. 7 is a fourth side view of a smart dimmer switch according to the present invention.
